WRINGER MOP

Filed June 27, 1927.

UNITED STATES PATENT OFFICE.

WILLIAM J. BARBER, OF DELPHOS, OHIO, ASSIGNOR TO THE DELPHOS MOP COMPANY,
OF DELPHOS, OHIO, A CORPORATION OF OHIO.

WRINGER MOP.

Application filed June 27, 1927. Serial No. 201,918.

This invention relates to wringer mops, and an object of the invention is to provide a new and improved connection between the handle and mop head to enable the mop cloth 5 to be wrung in a simple manner, and to be conveniently moved to mopping position. Other objects and advantages of the invention will appear as the description proceeds.

The invention is shown by way of illustration in the accompanying drawings, in which:

Fig. 1 is a perspective view of the mop head and a portion of the handle with the mop cloth removed; and Fig. 2 is a side elevation of the mop head and handle with the mop cloth attached and parts in wringing position.

The illustrated embodiment of the invention comprises a mop head or frame having 20 a relatively narrow plate 1 terminating in an enlarged end 2, and rising vertically from the sides of the plate 1 are ears or brackets 3, the front edges 4 being inclined rearwardly to permit the mop head to extend 25 underneath low articles of furniture without marring. The laterally spaced vertical brackets 3 are formed with elongate rearwardly inclined slots 5, only one of which appears on the drawing. The purpose 30 of the slots 5 will hereinafter appear.

One end of the plate 1 is bent around a wire frame part 6 to hold the latter in place, and the frame part 6 is bowed at the inner end to form the sides of the mop head. It 35 will be observed that the sides of the mop head are spaced a considerable distance apart so that a substantial portion of the mop cloth 2^a may be pressed against the surface 40 to be mopped.

The front edge portion of the enlarged plate 2 is also bent into retaining engagement with the wire frame part 6, the part 6 extending inwardly at the end of the plate 2 and terminating in legs 6^a. An upwardly-bent portion 7 extends from the edge of plate 2 between the legs 6^a of the wire frame part to eliminate a sharp edge for the mop cloth. An open loop 8 is formed on the outer ends of the legs 6^a and the separated 50 ends are bridged by a gate 9 pivoted to one of the legs by a pin 10 to allow the mop cloth to be readily attached or detached.

One end of the mop cloth engages the loop 8 and extends beneath the mop head, the

opposite end engaging a loop 11 of a wringer crank 12 journaled in a mop handle 13. The wringer crank 12 has an operating part 14 provided with a knob 14^a. The wire frame part 6 not only serves to spread the mop cloth over a relatively wide area, but 60 also exerts an even pressure on the loop 11 of the wringer crank to hold the operating part 14 in upright position. This prevents the operating part 14 and knob 14^a from getting wet when the mop cloth is submerged in water.

Embracing the end portion of the handle 13 is a sleeve 16 having depending ears 17 disposed between the upright brackets 3. Extending transversely through the ears 17 and into the slots 5 of the brackets, is a pin 18 having upset ends. Washers 19 on the pin 18 prevent disengagement thereof from the slots.

When it is desired to wring the mop cloth 2^a, the handle 13 is lifted to such an angle that by its weight the mop head is caused to drop downwardly, permitting the pin 18 to move upwardly relative to the slots 5 until it abuts against the opposite ends thereof. During this movement the mop head swings 80 to a position at approximately right angles to the handle, and the rear curled portion of the plate 1 which engages the bowed frame 6 may abut against the handle, as shown in Fig. 2. With the parts in this position, the mop cloth 2^a is loosened or slackened sufficient to enable it to be readily wrung by means of the wringer crank. It is apparent that between the handle and frame parts there 90 is a single pivotal sliding connection which is free and unrestricted so that the pin 18, which provides a pivotal axis for the relative swinging movement of the parts, is free to slide within the elongate guide slots 5, and when in one position at the inner ends of the slots, the parts are in position for use, but when at the outer ends of the slots the parts are free to swing to wringing position.

For mopping, the front or toe of the mop head first engages the surface to be mopped, and by a slight pressure on the handle, the remainder of the mop is brought into engagement. The connection between the handle and head is such that a direct uniform 100 pressure may be exerted against the mop cloth.

It is to be understood that I may use any

inclined guideway for accomplishing the purpose recited, although I have found the pin and slot connection particularly advantageous in this instance. Other changes and alterations in details of construction and arrangement may be effected without departing from the spirit of the invention.

What I claim as new and desire to secure by Letters Patent is:

10. 1. A wringer mop having a frame, a pair of upstanding ears on said frame, said ears having elongate slots, a handle, and a pin fixed to the end portion of said handle and slidably in said slots, said connection constituting the sole supporting connection between said parts.
20. 2. A wringer mop having a plate, upturned sides on said plate, a wire frame having its sides laterally spaced from said plate, a connection between opposite ends of said plate and frame, a loop at the outer end of said wire frame, said upturned sides having inclined slots, a handle, and a pin projecting laterally from said handle into said slots.
30. 3. A wringer mop having a head provided with an upwardly and rearwardly inclined guideway, the front end of said guideway being disposed intermediate the ends of the head but near the rear end thereof and the rear end of said guideway being in substantially vertical alignment with the rear end of the frame, and a handle having a part movable in said guideway, whereby when said part moves toward the upper end of said guideway the head may swing to a position at substantially right angles to the handle with a part of the head abutting the handle for wringing purposes.
40. 4. A wringer mop having a head provided with an upwardly and rearwardly inclined slot, the front end of said slot being disposed intermediate the ends of the head but near the rear end thereof and the rear end of said guideway being in substantially vertical alignment with the rear end of the frame, a handle, a part on the handle slidably in said slot, a wringer crank on the handle, and a mop cloth engaging said wringer crank and the front portion of the head, whereby said part may move to the upper end of the slot and the head move to a position at substantially right angles to the handle with the rear end portion of the head abutting the handle.
50. 5. A wringer mop having a frame provided with an upwardly and rearwardly extending guideway, and a handle slidably and pivotally mounted in said guideway, the upper portion of said guideway constituting a stop whereby said handle part may engage said stop to permit said frame to be swung to a position at substantially

right angles to said handle in position for wringing.

65

6. A wringer mop comprising a frame part constructed to receive a portion of a mop cloth, a handle part, an element on one part engageable with and having sliding connection with the other part and providing at its point of engagement with said other part an axis about which said parts may be swung relatively to each other and means on the handle part to receive an opposed portion of a mop cloth.

75

7. A wringer mop comprising a frame part having means at one end portion to receive a mop cloth, a handle part, a guideway on one part, and a member on the other part in slidable engagement with said guideway, said member providing at its point of engagement with said guideway an axis about which said parts may be swung relatively to each other, and means on the handle part to receive an opposed portion of the mop cloth.

85

8. A wringer mop comprising a frame part constructed to receive a mop cloth at one end thereof, a handle part, a wringer crank on said handle part to receive an opposed portion of a mop cloth, an inclined elongate guideway on one part, and a member on the other part in slidable engagement with said guideway, said member providing at its point of engagement with said guideway an axis about which said parts may be swung relatively to each other, whereby when said member is at the inner end of said guideway, the parts are in position for use to extend the mop cloth, and when at the outer end of the guideway, the parts may be swung toward each other to loosen the mop cloth for wringing purposes.

90

95

9. A wringer mop comprising a frame part constructed to receive a mop cloth at one end, a handle part, a single free pivotal and sliding connection between said parts, and means on the handle part to receive an opposed portion of a mop cloth whereby when in one position the parts are arranged for mopping, and when in another position the parts are arranged for wringing.

105

10. A wringer mop comprising a frame having a working surface, an element on the top of said frame forming a guide disposed at an angle to said surface, a handle having a part in pivotal and sliding engagement with said guide, and means on said handle to receive one end portion of a mop cloth, the outer end of said frame being constructed to receive the opposite end of the mop cloth.

115

In testimony whereof I have hereunto signed my name to this specification.

WILLIAM J. BARBER.
